DIAGNOSTIC COMPOSITION

Robert Bauer, Kalamazoo, Mich., and Ray L. Mast, Elkhart, Ind., assignors to Miles Laboratories, Inc., Elkhart, Ind., a corporation of Indiana
No Drawing. Filed May 15, 1959, Ser. No. 813,336
6 Claims. (Cl. 23—253)

This invention relates to a new and improved diagnostic composition and is particularly concerned with a diagnostic test which is useful for the qualitative detection and quantitative determination of glucose in biological fluids, such as urine, and wherein the reagent composition is incorporated upon a bibulous carrier.

The detection of glucose in urine as well as the determination of its concentration therein is of great importance for diabetic patients who must control their diets so as to regulate their sugar intake and who must frequently be guided in this regard by a regular check on urine glucose. But beyond its usefulness in regular urine testing on known diabetics by both patients and physicians, this glucose indicator may also be used efficiently in routine urinalyses in hospitals and physicians' offices, in diabetes detection screening programs, in the differentiation of glucosuria from other meliturias, and the like.

Because early diagnosis and continued control are so important in diabetes, a urine-sugar test, to be of greatest value, must be conveniently rapid, simple enough for any patient to learn with ease, accurate enough to serve the clinician, and sensitive enough to reflect variations in the patient's condition. Moreover, the reagent composition must be adequately stable.

Procedures for the detection of sugar in urine are well known in clinical chemistry. One such procedure utilizes Benedict's copper reduction test, another employs a self-heating alkaline copper reduction test in tablet form (U.S. Patent No. 2,387,244), still another involves a test which depends solely on the action of enzymes (U.S. application Ser. No. 514,395, filed June 9, 1955, by Alfred H. Free and assigned to the assignee of the present invention). These and other procedures have greatly contributed to the art of diagnosing for urine glucose.

We have now found a novel and highly useful glucose-detecting means which represents an important improvement and a fresh approach to the problem of determining glucose in various materials including body fluids, such as urine, by a technique that utilizes a diagnostic composition which rivals even the latest and most commonly used glucose tests.

Specifically, we have now found that a unique combination of a glucose oxidase system for determining glucose with a novel indicator system using an iodide-molybdate accelerator for detecting hydrogen peroxide offers a superior means for testing biological fluids for their glucose content.

A diagnostic composition according to the present invention comprises as essential constituents glucose oxidase, an iodide salt, such as potassium iodide, a molybdate salt, such as sodium molybdate, and a color-forming substance or indicator, such as 2,7-diaminofluorene.

The glucose oxidase (glucose aerodehydrogenase), as is well known, catalyzes the aerobic oxidation of glucose to produce gluconic acid (gluconolactone) and hydrogen peroxide. The iodide and molybdate salts, in turn, are capable of inducing the oxidation of indicators by hydrogen peroxide formed in the oxidation of glucose. The latter reaction may be represented by the following schematic equation:

2

The degree of blue color formation is immediately but accurately indicative of the glucose content of the fluid being tested.

The principle underlying the function of the iodide and molybdate salts as well as their coaction or interaction is not yet fully understood. However, it appears that, analytically, it is their role to serve as electron-transfer agents. We have found that due to their collective presence—with one intensifying the effect of the other—the reaction proceeds at a faster rate and lesser concentrations of hydrogen peroxide and, accordingly, glucose may be determined. These salts may therefore be referred to as accelerators and promoters which hasten and enhance the oxidation of the indicator substance by hydrogen peroxide.

The incorporation and use in this new glucose diagnostic of potassium iodide and sodium molybdate, both of which are commercially available, represents a substantial and significant advance in the art pertaining to glucose diagnostics. Glucose indicators in "stick" form presently on the market depend for the detection of hydrogen peroxide on the action of enzymes, such as peroxidases. The glucose indicator of the present invention, on the contrary, makes use of a non-enzymatic agent which permits a more accurately controllable and more definite composition. A very sensitive test for hydrogen peroxide and, accordingly, glucose is thus made possible.

In place of the potassium iodide and sodium molybdate it is also possible, and therefore contemplated, to employ other equivalent iodide and molybdate salts. For example, other iodides, such as sodium and ammonium iodides and other molybdates, such as potassium and ammonium molybdates may also be used. In lieu of the 2,7-diaminofluorene, o-tolidine, o-dianisidine, leucoindophenols, etc. would be satisfactory indicators.

From the detailed examples below it is evident that such additives are incorporated in the reagent composition as suitable protective, thickening, wetting, suspending agents and the like as well as inert dyes to impart thereto a uniform color background.

Furthermore, it is important to include an appropriate buffer system to maintain a desired pH range in the presence of urine. Although the pH range may vary between 4 to 7.5, an especially preferred pH is 6.7.

Although the test device itself may comprise the reagent composition in the form of a tablet, powder or other embodiment, we prefer to affix the reagent composition on bibulous base materials or carriers, such as strips or sticks of filter paper, by dissolving the components in a suitable solvent, impregnating the bibulous strips with the resulting solution, and drying the impregnated test strips. Embodying the diagnostic composition in the form of test sticks insures ease and simplicity of test procedure.

The invention will now be illustrated in greater detail, 55 but not limited, by the following examples:

EXAMPLE I

Formulation of the impregnating solution

60	Polyvinyl alcohol (PVA)	gm	1
	95% ethanol	ml	15
	Glycine	gm	3
	KI	gm	1
	Na ₂ MoO ₄ ·2H ₂ O	gm	0.5
	Gelatin	gm	0.4
65	FD & C Red #3	gm	0.015
	Glucose oxidase	gm	0.5
	2,7-diaminofluorene·2HCl	gm	0.3
	Phosphate buffer—pH 6.5	ml	20
	Water	ml	50
70	Total	ml	85

Preparation of impregnating solution

(1) 1 gm. of PVA is dissolved in 10 ml. of water by heating. To this is added 15 ml. of 95% ethanol and 10 ml. of a gelatin-dye solution prepared by dissolving 4 gm. of gelatin and 0.15 gm. of FD & C Red #3 in 100 ml. of boiling water.

(2) 3 gm. of glycine and 1 gm. of KI are dissolved in 10 ml. of boiling water and added to solution No. 1 and cooled.

(3) 0.5 gm. of glucose oxidase (16,000 units per gram) are dissolved in 10 ml. of water and added to solution No. 2.

(4) 0.3 gm. of 2,7-diaminofluorene dihydrochloride are dissolved in 5 ml. of water and added to solution No. 3.

(5) 20 ml. of phosphate buffer of pH 6.5 (prepared by dissolving 43.55 gm. of dibasic potassium phosphate (K_2HPO_4) and 39.0 gm. of monobasic sodium phosphate ($NaH_2PO_4 \cdot H_2O$) in water and bringing to a volume of 500 ml.) are added to solution No. 4 with constant stirring.

(6) Finally, 0.5 gm. of $Na_2MoO_4 \cdot 2H_2O$ are dissolved in 5 ml. of water and added slowly to solution No. 5 with constant stirring. The impregnating solution or mix is now ready for use.

Preparation of reagent strips

Bibulous strips, such as filter paper cut into narrow strips, are dipped into the impregnating solution so that through the process of submersion and capillary attraction about one-half inch of the strip at one end is completely impregnated. These strips are then dried in a drying tunnel or in a forced draft oven. The test portion of these strips is of a red color. It will be understood that other porous or absorbing materials, such as small sticks of wood, etc. and other methods of applying the impregnating solution and of drying the impregnated sticks may likewise be employed.

EXAMPLE II*Formulation of the impregnating solution:*

Algin	gm	0.3
Polyvinyl alcohol (PVA)	gm	1
Glycine	gm	3
KI	gm	1
Buffer	ml	10
Glucose oxidase	gm	0.5
2,7-diaminofluorene.2HCl	gm	0.3
95% ethanol	ml	15
Gelatin	gm	0.4
FD & C Red #3	gm	0.015
$Na_2MoO_4 \cdot 2H_2O$	gm	0.5
Water	ml	65
Total volume	ml	100

Preparation of the impregnating solution

(1) 0.3 gm. of algin are dissolved in 20 ml. of water.

(2) 1 gm. of PVA is dissolved in 10 ml. of water by heating and added to solution No. 1.

(3) 3 gm. of glycine and 1 gm. of KI are dissolved in 10 ml. of boiling water. 10 ml. of buffer (prepared by dissolving 436 gm. of dibasic potassium phosphate (K_2HPO_4) in 1000 ml. of water and adding thereto 290 ml. of 2.5 M phosphoric acid) are added to the glycine-KI solution which is then added to solution No. 2.

(4) 0.5 gm. of glucose oxidase (16,000 u./gm.) are dissolved in 5 ml. of water and added to solution No. 3.

(5) 0.3 gm. of 2,7-diaminofluorene dihydrochloride are dissolved in 5 ml. of water and 15 ml. of 95% ethanol. This is added to solution No. 4 with constant stirring.

(6) 10 ml. of gelatin-dye solution (prepared by dis-

solving 4 gm. of gelatin and 0.15 gm. of FD & C Red #3 in 100 ml. of boiling water) are added to solution No. 5.

(7) 0.5 gm. of $Na_2MoO_4 \cdot 2H_2O$ are dissolved in 5 ml. of water and added to solution No. 6. The impregnating solution or mix is now ready for use.

Test strips are then prepared in accordance with the procedure recited in Example I.

EXAMPLE III*Formulation of the impregnating solution*

Algin	gm	0.5
KI	gm	1
$Na_2MoO_4 \cdot 2H_2O$	gm	0.5
Glycine	gm	3
Gelatin	gm	0.4
FD & C Red #3	gm	0.015
Glucose oxidase	gm	0.5
20 Cellex-p (DAF treated)	gm	4
Water	ml	80

Preparation of the impregnating solution

(1) 0.5 gm. of algin are dissolved in 30 ml. of water.

(2) 1 gm. of KI, 3 gm. of glycine and 0.5 gm. of $Na_2MoO_4 \cdot 2H_2O$ are dissolved in 20 ml. of hot water. 10 ml. of 4% gelatin-dye solution is added to this solution. The gelatin-dye solution is prepared as described in Example I.

(3) Solution No. 2 is now added to solution No. 1 to give solution No. 3.

(4) 0.5 gm. of glucose oxidase (16,000 units per gram) is dissolved in 10 ml. of water and added to solution No. 3.

(5) Finally, there is added to the impregnating mixture 4 gm. of Cellex-p, treated with 2,7-diaminofluorene in accordance with the following procedure:

Two grams of 2,7-diaminofluorene dihydrochloride are dissolved in 100 ml. of water. Twenty grams of cation exchange cellulose (Cellex-p, Bio-Rad Laboratories), are mixed with this solution and left standing for 30 minutes. The mix is periodically agitated during this time. The cellulose is filtered through a Büchner funnel and washed four times by resuspending it in 100 ml. portions of water. The cellulose is then dried before use.

The use in this embodiment of cation exchange cellulose has a two-fold purpose: it maintains the indicator in suspension so as to prevent it from precipitating, and it serves as a buffer for the reagent composition. These functions in the embodiments of Examples I and II are performed, respectively, by polyvinyl alcohol and the buffer system.

Procedure of testing

In use, an impregnated strip, made as described in the above examples, is dipped into the liquid specimen to be tested. When contacted with urine containing glucose,

60 a test strip will give a positive reaction in about 5 to 30 seconds evidenced by various shades of blue color as follows:

With urine containing 1% or 2% glucose an intense deep blue color develops, while with urine containing as little as 0.1% or even less of glucose, the red color of the impregnated strip changes to a distinctly light blue color. With urines containing from 0.1 to 1% of glucose the blue colors which develop are of intermediate intensities: the urine having the higher glucose content produces the deeper color. When dipped in urine containing no glucose, the strips undergo no color change. A simple color chart based on this phenomenon may be conveniently prepared for use in testing for urine glucose.

70 In addition to the compositions described in the above examples illustrating optimum contents variations in

amounts of components are permissible as shown by the following chart:

Glucose oxidase	4000-16000 units.
Potassium iodide	0.25-1.5 gm.
Sodium molybdate	0.1-1.5 gm.
2,7-diaminofluorene.2HCl	0.2-1.0 gm.
Buffer	0.1-0.3 molar (pH 4.0-7.5).
Polyvinyl alcohol	0-3 gm.
Algin	0-0.5 gm.
Glycine	0-12 gm.
Gelatin	0-1.0 gm.
FD & C Red #3	0-015 gm.

The impregnated solutions prepared in accordance with any of the above examples as well as test strips impregnated with any of these solutions were found to be very stable. However, it is recommended that the strips be stored in brown bottles containing desiccant packs.

In summary, this invention pertains to a diagnostic test for the detection of glucose in body fluids, especially in urine, consisting of a bibulous strip or stick that has been impregnated with a composition comprising glucose oxidase, potassium iodide, sodium molybdate and 2,7-diaminofluorene which is oxidizable by hydrogen peroxide formed in the glucose oxidase-catalyzed decomposition of glucose in the presence of said iodide and molybdate salts.

What is claimed is:

1. A diagnostic composition for detecting glucose which comprises glucose oxidase, an iodide salt selected from the group consisting of potassium iodide, sodium iodide, and ammonium iodide, a molybdate salt for intensifying the action of the iodide and selected from the group consisting of sodium molybdate, potassium molybdate, and ammonium molybdate and a color-forming substance oxidizable by hydrogen peroxide in the presence of said iodide and molybdate salts.

2. A diagnostic composition for detecting glucose which comprises glucose oxidase, an iodide salt selected from the group consisting of potassium iodide, sodium iodide,
